DRAWING PRESS

Howard F. MacMillin, Mount Gilead, Ohio, assignor to The Hydraulic Development Corp. Inc., Wilmington, Del., a corporation of Delaware

Application October 17, 1938, Serial No. 235,316

3 Claims. (Cl. 113—45)

This invention relates to drawing presses, and in particular, to such presses having blank holders for holding the margins of the workpiece during operations by the drawing plunger.

5 One object of this invention is to provide a drawing press having a main platen for holding the drawing die, and a blank holder platen located on the opposite side of the main platen from the workpiece and engaging the workpiece by members passing through the main platen.

Another object is to provide such a drawing press, wherein a plurality of work-holding members is provided for use with a single blank holder platen in order to adapt the drawing press 10 to various sizes and shapes of drawing dies and workpieces.

Another object is to provide a drawing press having a main platen and a blank holder platen on the opposite side of the main platen from the workpiece, with means for generating pressure fluid to operate the blank holder platen in response to the motion of the main platen.

Another object is to provide such a drawing press as set forth in the preceding paragraph, 20 wherein the blank holder rams for operating the blank holder platen are arranged so that the pressure generation, due to the motion of the main platen, acts in a direction assisting the main platen, and without any substantial opposing force.

In the drawings:

Figure 1 is a diagrammatic view in central vertical section through the principal operating elements of a drawing press according to the 35 present invention, with a suitable operating circuit.

Figure 2 is a cross section along the line 2—2 in Figure 1.

Figure 3 is a front elevation of a commercial 40 form of drawing press embodying the invention of Figures 1 and 2.

Figure 4 is a cross section along the line 4—4 in Figure 3.

45 General arrangement

In general, the drawing press of this invention consists of a bed for supporting the hollow die, a main plunger and platen for supporting and moving the punch or forming die, and a blank 50 holder platen disposed on the opposite side of the main platen from the workpiece. Provision is made for plungers to operate the blank holder platen by means of pressure generated in response to the motion of the main platen, and in 55 such manner that the operation of the blank

holder plungers does not subtract any substantial amount of force from the operation of the main plunger and main platen. The workpiece blank is held in position on the hollow die during the drawing operation by a hold-down plate 5 which is connected to the blank holder platen by means of rods running through holes in the main platen. If the drawing press is a vertical form of press, as shown in the drawings, then the blank holder platen according to the present 10 invention is located above the main platen for a downwardly-acting main plunger and main platen.

Hitherto, where drawing presses have been provided with blank holder platens beneath the 15 main platen and directly in contact with the workpiece, it has been necessary to cut an aperture in the blank holder platen closely corresponding with the size and shape of the drawing die or punch. Thus, if a variety of workpieces of 20 widely varying sizes or shapes was to be drawn on the same press, it was necessary to change blank holder platens in order that the new punch and blank holder platen would correspond closely in 25 size and shape. It has also been necessary to provide a blank holder platen which is stiff enough to resist bending stresses, hence, the necessity for providing a number of blank holder platens in order to accommodate the press to varying sizes and shapes of workpieces, resulting in very expensive 30 equipment and the limitation of flexibility of such equipment for producing varying shapes of workpieces.

According to the present invention, by placing 35 the blank holder on the opposite side of the main platen from the workpiece, only one blank holder platen is required for all jobs within the capacity of the press, and this blank holder platen can be made as heavy and as rigid as desired without requiring any additional blank holder platens. Instead, a number of comparatively light-weight 40 and relatively inexpensive hold-down plates for holding the workpiece are provided of a variety of shapes and sizes to suit corresponding workpieces. These hold-down plates are connected to the blank holder platen by means of rods passing through holes in the main platen and the latter can be drilled with numerous holes in order to render it adaptable to all varieties of workpieces. The pressure-applying mechanism employed with the press of the present invention is likewise adaptable to exerting different pressures 50 at different portions of the workpiece, according to the requirements of the particular job. 55

Construction

Referring to the drawings in detail, Figure 1 shows diagrammatically the principal working elements of a drawing press according to the present invention, together with a suitable operating circuit. The press of Figure 1 consists of a bed 10 and a head 11, the strain rods and other usual frame members being omitted to clarify the disclosure. Mounted upon the bed 10 is the hollow die 12 with the workpiece 13 supported thereon, and having a die cavity 14 for receiving the drawing die or punch 15. The latter is mounted upon the main platen 16, which in turn, is connected to the main plunger 17 having a piston head 18 reciprocable within the cylinder bore 19 of the main cylinder 20 mounted on the press head 11. A packing 21 and gland 22 prevent leakage around the main plunger 17, and ports 23 and 24 serve for the distribution of fluid to the main cylinder bore 19.

The press head 11 is provided with blank holder balancing cylinders 25 having bores 26 into which the hollow blank holder plungers 27 are reciprocable, leakage being prevented by the packings 28 and glands 29. The cylinder bores 26 are provided with intake ports 30 and discharge ports 31 and 32. The blank holder plungers 27 are secured to the blank holder platen 33 by means of the split rings 34 operating in grooves 35, and extend downwardly into cylinder bores 36 within the main platen 16, leakage being prevented by the packings 37 and glands 38. The blank holder platen 33 is likewise provided with an aperture 39 for the passage of the main plunger 17 and carries rods 40 extending through holes 41 in the main platen 16, the rods 40 being secured at their lower ends to the hold-down plate 42 having an aperture 43 for the passage of the drawing die or punch 15.

The blank holder plungers 27 are provided with heads 44 reciprocable in the bores 36, and also with L-shaped passages 45 running from adjacent the heads 44 to the opposite ends of the blank holder plungers 27, and there opening into the cylinder bores 26 in the blank holder balancing cylinders 25. The cylinder bores 36 are provided at their lower ends with leakage vanes 46, which provide for drainage of fluid leaking past the blank holder plunger heads 44, these vanes 46 being preferably connected by piping (not shown) back to the fluid tank 47 mounted on the press head 11. In practice, it will be understood that the shapes and sizes of the dies 14 and 15 will vary according to the workpiece to be produced, thereby varying the shape of the aperture 43 in the hold-down plates 42. A variety of hold-down plates 42 can be provided, however, and connected to the blank holder platen 33 by the rods 40.

Press-operating circuit

The drawing press of this invention may be operated by a number of hydraulic circuits, that shown in Figure 1 being suitable for applying different pressures at different points on the periphery of the workpiece 13. In the circuit shown in Figure 1 there is provided a fluid pressure pump 48, having a suction line 49 running back to the tank 47 and a discharge line 50 running to the main control valve 51, the latter being a four-way valve for reversing the flow of the pump 48 relatively to the main cylinder 20, 75 at the same time connecting the line which is

not under pressure to the tank 47 by means of the exhaust line 52. From the main control valve 51 the lines 53 and 54 run to the ports 23 and 24 in the main cylinder bore 19.

Each blank holder balancing cylinder 25 is provided with a suction line 55 connected to the port 30, and terminating in a check valve 56 opening toward the port 30. The cylinders 25 are also provided with exhaust lines 57 passing through check valves 58 opening in a direction 10 away from the ports 31 and uniting in the line 59 connected to the two-way platen-operated valve 60. The latter is provided with an exhaust line 61 extending into the tank 47 and is operated by a valve rod 62 by means of a cam 63, engaged and shifted by a platen arm 64 extending outwardly from the main platen 16. Connected to the ports 32 in the blank holder cylinders 25 are additional discharge lines 65 having pressure gauges 66 associated therewith for indicating the pressures in the blank holder cylinders 25. Connected to the lines 65 are the blank holder relief valves 67, which may be set so that at predetermined pressures they discharge fluid from the lines 65 into the exhaust lines 68. Safety valves 69 are likewise connected between the lines 65 and 68 and set at higher pressures than the relief valves 67 in order to prevent the development of excessive pressures in case the blank holder relief valves 67 should accidentally become inoperative.

Operation

In the operation of the drawing press shown in Figures 1 and 2, the pump 48 is started and the workpiece blank 13 is placed on top of the hollow die 12 and beneath the hold-down plate 42, which is suspended from the rods 40. Pressure is then supplied to the main ram area above the piston head 18 by shifting the main control valve 51, so that the pump 48 discharges pressure through the lines 50 and 53, the line 54 opening into the space beneath the main plunger head 18 being connected to the exhaust line 52. It will be understood that the usual surge valve system may also be applied to the main cylinder 20 to assist and accelerate the gravitational descent of the main plunger 17, as is well known to those skilled in the hydraulics art, but this system has been omitted to simplify the disclosure.

Under these circumstances the main plunger 17, main platen 16 and drawing die or punch 15 descend. The blank holder platen 33 likewise descends and the blank holder plungers 27 draw oil or other operating fluid into the blank holder cylinders 25, through the check valves 56 and lines 55. By the time the hold-down plate 42 reaches the workpiece blank 13 the platen arm 64 has engaged and shifted the cam 63 and valve rod 62 downwardly, closing the normally open two-way valve 60. After this occurs fluid cannot escape through the lines 57 and 59 and the check valves 58. Upon engaging the workpiece blank 13 the hold-down plate 42 halts, and consequently halts the blank holder platen 33 through the rods 40 connected thereto. The main platen 16, however, continues to move downward, hence, the cylinder bores 36 are pulled downwardly away from the blank holder plunger heads 44. Fluid in the cylinder bores 36 above the heads 44 cannot escape except through the plunger passages 45, into the blank holder balancing cylinders 25. From these cylinders it cannot escape except through the pressure relief valves 67 or 75

safety valves 69. As the safety valves 69 are set for higher pressures than the relief valves 67, pressure builds up in each of the blank holder balancing cylinders 25 as the main platen 16 continues to move downwardly, and by its motion generates fluid pressure within its cylinder bores 36.

When the pressure thus generated within the blank holder balancing cylinders 25 reaches the setting of its respective relief valve 67, the latter opens and discharges into the exhaust line 68 all fluid in excess of its set pressure, the discharged fluid escaping to the tank 47. The pressure thus generated within the blank holder balancing cylinders 25 acts upon the annular piston areas 70 upon the upper ends thereof, so as to urge the blank holder plungers 27 and blank holder platen 33 downwardly, thereby applying pressure through the rods 40 to the hold-down plate 42, and holding the workpiece blank 13 against the hollow die 12. It will be observed that in this arrangement the pressure generated within the main platen cylinder bores 36 urges the blank holder plunger 27 downwardly so that the only force that is subtracted from the force exerted by the main plunger 17 is that due to the pressure acting upon the annular areas immediately above the blank holder plunger heads 44, and constituting differential areas representing the difference between the cross sectional areas of the plungers 27 and their heads 44.

As the main platen 16 continues to move downwardly, the punch or drawing die 15 engages the workpiece blank 13 and forces its central portion downwardly into the die cavity 14. At the same time, however, the blank 13 is allowed to slip inwardly at its edges because the pressure upon the hold-down plate 42 is so adjusted, by means of the pressure relief valves 67, as to permit the proper amount of slippage in the blank 13 during the drawing operation. When the main platen 16 and drawing die 15 have moved the proper distance, or have exerted the desired pressure, the main control valve 51 is shifted so as to connect the pump pressure line with the pull-back line 54 while connecting the pressing line 53 with the exhaust line 52. Pressure fluid is then exerted against the under side of the main plunger head 18, causing the main plunger 17 and main platen 16 to rise on their retraction strokes. The blank holder platen 33, however, moves a relatively small amount at first because of the fluid trapped in the blank holder balancing cylinders 25. A slight amount of motion may occur, however, due to the slight withdrawal of fluid from the cylinders 25 through the passages 45 into the main platen cylinder bores 36, as the latter move upwardly with relation to the blank holder plunger heads 44, thereby creating a slight void in the cylinder bores 36.

Because of the weight of the blank holder platen 33, blank holder plungers 27, rods 40 and hold-down plate 42, however, the latter will remain temporarily resting against the blank 13 during the first part of the retraction stroke of the main platen 16 and drawing die 15. Under these conditions the hold-down plate 42 strips the workpiece from the drawing die or punch 15, after which the platen arm 64 in rising releases the cam 63 and valve rod 62 so as to permit the opening of the normally open two-way valve 60, thereby permitting the fluid in the blank holder cylinders 25 to exhaust through the lines 57, 59 and 61 and the check valves 58 and two-way valve 60.

After the two-way valve 60 has opened in this manner, therefore, the main platen 16 will engage the annular shoulders 11 upon the upper ends of the rods 40 and carry the blank holder platen 33 and its connected parts upward for the remainder of the retraction stroke of the main platen 16. The check valves 58 prevent equalization of the pressure in the several blank holder cylinders 25 during the blank-holding operation, thereby permitting different blank-holding pressures to be exerted by different blank-holding plungers 27. It will be obvious, however, that the check valves 58 may be omitted and the same blank-holding pressures thereby applied to all of the blank-holding plungers 27 if the user so desires. In the latter arrangement a single pressure relief valve 67 could be used to exert the single blank-holding pressure.

Commercial form of press

20

The press of Figures 1 and 2 is illustrated in diagrammatic form. Figures 3 and 4, however, show a press having the blank-holding platen above the main platen and embodying the features of the invention in commercial form. This commercial form of press consists of a bed 72 and a head 73, interconnected by strain rods 74 terminating in the nuts 75 threaded upon the ends thereof. The press head 73 carries a main cylinder 76 and a tank 77, together with the blank 80 holder cylinders 78, similar to the blank holder cylinders 25 previously described. Mounted upon the press head 73 is a pump 79 operated by an electric motor 80.

The blank holder cylinders 78 contain hollow blank holder plungers 81 intermediately connected to the blank holder platen 82, and at their lower ends passing into pressure-generating cylinders 83 mounted within the main platen 84. The rods 85 constitute connecting members between the blank holder platen 82 and the hold-down plate 86. The main platen 84 is actuated by the main plunger 87 connected thereto and extending into the main cylinder 76, in a manner similar to that shown and described in connection with Figure 1. In Figures 3 and 4, however, the punch and hollow die have been omitted because the shapes and sizes of these members vary according to the particular kind of workpiece to be produced. The main platen 84 carries a platen arm 88 arranged to engage a collar 89 upon the control rod 90, reciprocably supported in the brackets 91 and 92.

By way of variation, however, the pump 79 is of the reversible variable delivery type having a control member 93 operating a servomotor, in a manner well known to those skilled in the art, and controlled by the control rod 90 through suitable mechanism. The control rod 90 may also be operated manually by means of the hand lever 94, mounted as at 95, upon the press bed 72. A control panel 96, mounted on the press, contains pressure gauges 97 and 98 and a push-button assembly 99 for carrying the various electrical switches employed in the control of the press.

It will be understood that I desire to comprehend within my invention such modifications as come within the scope of the claims, and the invention.

Having thus fully described my invention, what I claim as new and desire to secure by Letters Patent, is:

1. In a drawing press, a work support, a frame, a press head having a main cylinder and a blank-holder-operating cylinder, a main plunger re-

70

75

75

- ciprocable in said main cylinder, a hollow blank holder plunger reciprocable in said blank-holder-operating cylinder and having a head thereon, a main platen connected to said main plunger and having a cylinder for receiving said blank holder plunger head whereby relative movement between said cylinder and head will generate fluid pressure, a blank holder platen connected to said blank holder plunger and located between said main platen and press head, a work-holding member mounted on the opposite side of said main platen from said blank holder platen, and a connecting element extending between said work-holding member and said blank holder platen, said work-holding member being adapted to be disconnected from the blank holder platen for replacement by another work-holding member.
2. In a drawing press, a work support, a frame, a press head having a main cylinder and a blank-holder-operating cylinder, a main plunger reciprocable in said main cylinder, a hollow blank holder plunger reciprocable in said blank-holder-operating cylinder and having a head thereon, a main platen connected to said main plunger and having a cylinder for receiving said blank holder plunger head whereby relative movement between said cylinder and head will generate fluid pressure, a blank holder platen connected to said blank holder plunger and located between said main platen and press head, a work-holding member mounted on the opposite side of said main platen from said blank holder platen, and detachably connected with said blank holder

platens by a connecting element extending between said work-holding member and said blank holder platen, and means responsive to the attainment of a predetermined pressure in said blank-holder-operating cylinder for releasing fluid therefrom. 5

3. In a drawing press, a work support, a frame, a press head having a main cylinder and a blank-holder-operating cylinder, a main plunger reciprocable in said main cylinder, a hollow 10 blank holder plunger reciprocable in said blank-holder-operating cylinder and having a head thereon, a main platen connected to said main plunger and having a cylinder for receiving said blank holder plunger head whereby relative 15 movement between said cylinder and head will generate fluid pressure, a blank holder platen connected to said blank holder plunger and located between said main plate, and press head, a movable work-holding member mounted on the opposite side of said main platen, said work-holding member being detachably connected with said blank holder platen by a connecting element extending through said main platen, means responsive 20 to the attainment of a predetermined pressure in said blank-holder-operating cylinder for releasing fluid therefrom, a tank, a conduit interconnecting said fluid-releasing means with said tank, and a valve in said conduit closable 25 in response to a predetermined travel of said main platen for preventing release of fluid through said conduit. 30

HOWARD F. MACMILLIN.
